UNITED STATES PATENT OFFICE

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed January 3, 1921. Serial No. 434,422.

My invention relates to a starter for an engine such as an internal combustion engine, and the object thereof is to provide a simple and efficient drive or transmission for such engine starter. This drive is of the type operated manually for engagement with the engine member such as the flywheel and operated automatically for disengagement therefrom, the manual operating connections for such drive being capable of actuating the electrical contact or switch in the circuit for the electrical starting motor. The construction and arrangement of my drive are such that it is impossible to make such electrical contact until after the engagement of the driving member of the drive with the engine member thereby preventing the possibility of injury to any of the parts in case of accidental operation of the operating connections when the engine is running. Moreover, this construction and arrangement are such that in the event of abutting of the driving member of the drive against the engine member, such driving member is automatically slightly turned so as to result in proper engagement with the engine member, this result being accomplished by a continued movement of the operating connections and before any possibility of the closing of the electrical circuit of the starting motor. Other features of advantage and utility in my construction will be apparent from the description herein-after given.

In the drawings Fig. 1 is a sectional elevation of a starter apparatus embodying my invention and illustrating the drive proper in elevation, the section being taken on the line 1—1 of Fig. 3; Fig. 2 a view similar to Fig. 1 but showing the drive in section; Fig. 3 an end view of the starter apparatus; Figs. 4 and 5 sections taken on the same section line of Fig. 1 but looking in opposite directions as indicated by the arrows corresponding to said figures; Fig. 6 an elevation of the intermediate sleeve and Fig. 7 a diagram illustrating different positions of the intermediate sleeve.

Referring to the embodiment of my invention as herein shown, the same is of the single reduction type, that is the drive is op-

erated directly by the starter motor and not indirectly as by means of reduction gearing, and moreover the drive is of the so-called outboard type in which the driving member or pinion moves outwardly when meshing with the engine member or flywheel. However, it will be understood that my invention is equally applicable to the double reduction type and also to the inboard type of drive.

As shown, the electrical starting motor 1 is provided at one end with a casing 2 secured thereto in suitable manner as by means of the bolts 3, such casing being cut away towards its outer end so as to admit the engine member or gear ring 4 of the flywheel. The motor is provided with an extended armature shaft 5 which has a bearing 6 in the outer end of the casing. The drive or transmission is contained within this casing and is mounted upon and driven by this armature shaft which thus constitutes the driving shaft.

The drive, which is a variety of the screw shaft type, comprises a hollow screw shaft or sleeve and having screw threads 7 intermediate its length, a smooth portion 8, a stop nut 9 at its outer end and a driven head 10 at its inner end. This head is drivingly connected with a driving head 11 by means of a yielding driving connection such as a coiled driving spring 12 whose opposite ends are anchored to the heads 10—11 by means of the studs or bolts 13 and 14. The latter stud passes through the head 11 and partially enters the shaft 5 and thereby secures that head to the driving shaft 5.

The driving member consists of a pinion 15 having a smooth central bore and adapted to travel longitudinally along the screw threaded portion and also the smooth portion of the screw shaft, and also to rotate with such shaft after it has been clamped thereto in the manner hereinafter explained. This pinion is preferably held in its normal or home position shown in Figs. 1 and 2 by a yielding means which here consists of a coiled spring 16 encircling the smooth or plain portion of the screw shaft and bearing against, respectively, the nut 9 and the collar 17 loosely mounted on such portion of

the shaft. This collar is of the peculiar shape shown in Fig. 2, that is, it is of two diameters with the spring entering the larger diameter and with the smaller diameter adapted to enter the forward end of the bore of the pinion.

This pinion is provided at its inner end with a ring or flange 18 which is here smooth on its inner face except for an annular ring 10 of teeth 19 at the margin thereof.

The actuating member here consists of a nut 20 threaded on the screw thread 7 and adapted to automatically travel longitudinally along the screw shaft when the latter is 15 rotated and to rotate with such shaft after it has clamped the pinion thereto by its screw action, and also to automatically travel longitudinally in the opposite direction when the pinion is automatically disengaged from the 20 flywheel. This nut is provided with a flange 21 of lesser diameter than the flange 18 and with its margin within the line of teeth 19.

Within the casing 2 and encircling a portion of the drive there is mounted for longitudinal and rotary movement a shifting member or sleeve 22 which is contracted or truncated, conical in form, at its outer end and provided at its outer edge with a series of teeth 23 adapted to engage the teeth 19 of the flange in its shifting movement. This sleeve is provided at its inner end with a ring 24 secured thereto in suitable manner as by means of the radial pins 25 which are screw threaded into both the sleeve and the 53 ring.

A second or intermediate sleeve 26 is operatively connected with the sleeve 22 in such manner that the latter is shifted longitudinally in unison with the sleeve 26 and also is capable of partial rotary or annular movement with relation thereto. To this end the sleeve extends into the central bore of the ring 24 and the pins 25 which project into said bore extend into and cooperate with inclined slots 27 formed in opposite sides of the sleeve 26. Suitable yielding means, such as the coiled spring 28, serves to hold these two sleeves in their normal position shown in Figs. 1 and 2.

50 The sleeve 26 may be operated manually or pedally but for convenience I will use the word "manually" as a generic term for both operations. As shown, the casing 2 is provided with two parallel vertical brackets 29 in which is arranged a shaft 30, on which there is mounted a shifter in the form of a bell-crank consisting of the two depending parallel arms 31 and the upwardly extending operating arm 32 which obviously may be operated directly by the hand or foot of the operator or connected with any linkage or the like. The depending arms 31 are operatively connected with the sleeve 26 by means of the pins 33 on such sleeve and the slots 34 at the ends of such arms.

The operating connection is adapted to actuate the electrical contact of the starting motor when such connection is in a pre-determined position, at which time the pinion 15 is in engagement with the flywheel. This 7 electrical contact is controlled by the switch 35 whose button 36 is arranged in the path of movement of the adjustable screw 37 so that when the bell crank is rocked in an anti-clockwise direction the switch will be operated. 7

Describing a cycle of operation and starting with the parts in their normal position as shown in Fig. 2, when the operating connection 32 is moved or rocked to the left the first action will be the shifting of the sleeves 26 and 22 longitudinally to the right, whereupon, after a short travel, the teeth 23 will engage the teeth 19 so that continued longitudinal movement of the sleeve 22 will bodily shift the pinion 15 to the right and into mesh with the flywheel teeth. Just prior to the time when the pinion is in full mesh with the flywheel, the switch will be operated and the motor will be rotated with the result that the screw shaft will be rotated and the nut 20 will be advanced longitudinally until it comes into contact with the pinion whereupon it will shift the pinion against the stop nut 9 and the screw action of such nut will clamp the pinion to the screw shaft and cause such pinion to rotate with the shaft and consequently rotate the flywheel. When the pressure against the operating connection 32 is relieved the same, together with the two sleeves, will be restored to normal position by 10 the springs 38. When the engine starts on its own power the pinion and the nut 20 will be automatically restored to normal position.

In case there is resistance to the longitudinal movement of the pinion, as for instance, when the pinion teeth and flywheel teeth abut end to end, the construction is such that there will be a relative longitudinal movement of the intermediate sleeve with respect to the shifting sleeve, which movement will be 11 against the compression of the spring 28. This longitudinal movement causes a slight rotation of the shifting sleeve through the functioning of the pins 25 in the slots 27, and on account of the friction between the shifting sleeve and the flange of the pinion, particularly as increased by the presence of the teeth 19 and 23, the slight rotation of the shifting sleeve will be imparted to the pinion so as to cause registry of the pinion teeth and the flywheel teeth, whereupon the spring 28 will cause the pinion to move longitudinally into mesh with the flywheel. Thereupon the further movement of the operating connection 32 will, as before, cause electrical contact and the rotation of the starting motor and the cranking of the engine. The possible longitudinal relative movement of the two sleeves is limited by the length of the spiral slots 27, so that under no circumstances, as 130

for instance, if the engine is running, will it be possible to make electrical contact unless and until actual mesh of the pinion has first occurred.

Referring to the diagrammatic showing in Fig. 7 of the sequence of operations above referred to, the bottom line represents the total length of travel of the intermediate sleeve and the different positions marked by the arrows on the top line indicate the different positions of such sleeve at the time of the different actions or positions of the shifting sleeve and pinion. The intermediate sleeve 26 in its movement from the end of the line to the arrow A shifts the sleeve 22 the distance corresponding to the clearance before the latter sleeve engages the pinion flange. In the movement of the sleeve 26 from position A to position B the pinion is moved longitudinally to take up the clearance between the normal position of such pinion and the meshing end of the flywheel teeth. In case of abutting of these teeth the next movement from point B to point C, which is controlled in length by the length of the spiral slots, is taken up in the slight rotation of the pinion, and it is not until some point subsequent to the last mentioned one and which is before the end of the total travel, such as the point D, that the electrical contact is made. During this shifting movement of the pinion, the nut 20 stands still, but the moment the motor rotates it moves longitudinally to the right and into contact with the pinion, in the manner hereinbefore explained. During this longitudinal movement of the nut, the motor is not under load and is therefore permitted to properly and sufficiently accelerate.

It will be understood that in case of failure to properly adjust the apparatus, that is more particularly to adjust the screw 37, if electrical contact is made too early, the drive operates entirely as a manual shift, unless electrical contact should actually be made before the pinion has been shifted as far as the flywheel, in which latter event automatic mesh will be accomplished.

I claim:

1. An engine starter drive including in combination with a starting motor and with a member of the engine to be started, a driving member adapted to be shifted into operative engagement with the engine member and to be driven by the motor, and an operating device for controlling the shifting of said driving member, said device including two telescoping sleeves mounted for normal longitudinal movement together and having spiral slot and pin connection with each other for angular movement one with respect to the other when the longitudinal movement of the former is obstructed, such former sleeve being adapted to shift the driving member longitudinally and to impart its angular movement thereto, and a casing enclosing the

drive and having a cylindrical bearing in its interior, such bearing receiving such former sleeve.

2. An engine starter drive including in combination with a starting motor and with a member of the engine to be started, a driving member adapted to be shifted into operative engagement with the engine member and to be driven by the motor, and an operating device for controlling the shifting of said driving member, said device including two telescoping sleeves mounted for normal longitudinal movement together and having spiral slot and pin connection with each other for angular movement one with respect to the other when the longitudinal movement of the former is obstructed, such former sleeve being adapted to shift the driving member longitudinally and to impart its angular movement thereto, said former sleeve and the driving member having complementary engaging surfaces to assure said imparting of angular movement to the driving member.

3. An engine starter drive including in combination with a starting motor and with a member of the engine to be started, a driving member adapted to be shifted into operative engagement with the engine member and to be driven by the motor, and an operating device for controlling the shifting of said driving member, said device including two longitudinal sleeves having spiral slot and pin connection with each other for longitudinal movement together and for angular movement one with respect to the other when the longitudinal movement of the former is obstructed, such former sleeve being adapted to shift the driving member longitudinally and to impart its angular movement thereto, said driving member having a ring flange and said former sleeve having a contracted end adapted to engage such flange.

4. An engine starter drive including in combination with a starting motor and with a member of the engine to be started, a driving member adapted to be shifted into operative engagement with the engine member and to be driven by the motor, and an operating device for controlling the shifting of said driving member, said device including two longitudinal sleeves having spiral slot and pin connection with each other for longitudinal movement together and for angular movement one with respect to the other when the longitudinal movement of the former is obstructed, such former sleeve being adapted to shift the driving member longitudinally and to impart its angular movement thereto, said driving member having a ring flange provided with teeth, and said former sleeve having a contracted end terminating in teeth to engage the teeth of the flange.

5. An engine starter drive including, in combination with a starting motor and with a member of the engine to be started, a ro-

5 rotatable screw shaft, a pinion mounted for free longitudinal movement thereon and adapted to mesh with the engine member, an actuating member threaded on the shaft and adapted to advance longitudinally thereon to clamp the pinion thereto for rotary movement, and means for shifting the pinion into mesh with the engine member.

6. An engine starter drive including, in
10 combination with a starting motor and with a member of the engine to be started, a rotatable screw shaft, a pinion mounted for free longitudinal movement thereon and adapted to mesh with the engine member, an
15 actuating member threaded on the shaft and adapted to advance longitudinally thereon to clamp the pinion thereto for rotary movement, and combined means for shifting the pinion into mesh with the engine member
20 and for imparting to said pinion a rotary, mesh-insuring movement in the event said pinion abuts said engine member.

7. An engine starter drive including, in combination with a starting motor and with
25 a member of the engine to be started, a rotatable screw shaft, a pinion mounted for free longitudinal movement thereon and adapted to mesh with the engine member, an actuating member threaded on the shaft and
30 adapted to advance longitudinally thereon to clamp the pinion thereto for rotary movement, and means for shifting the pinion into mesh with the engine member, and including two operating members, one rotatably displaceable relative to the other and adapted and arranged to rotatably move the pinion, and connections between said members for relatively displacing the said pinion moving member if said pinion abuts the engine
35 member.

40 8. An engine starter drive including a screw threaded shaft, a driving member loosely mounted thereon, a control member threaded on the shaft and actuating such
45 driving member, said members having cooperating flanges, the one on the driving member being of the greater diameter, a longitudinally movable sleeve encircling said shaft and control member and, when moved longitudinally, adapted to engage and move the driving member longitudinally to engage a member of the engine to be started, and a second sleeve operatively connected to one end of the first sleeve by spiral slot and pin
55 connection.

50 9. An engine starter drive including a rotatable driving shaft, a screw threaded hollow shaft mounted on the driving shaft, a yielding driving connection between the two
60 shafts, a pinion loosely mounted on the screw shaft, a nut threaded on the screw shaft and adapted to actuate the pinion, a longitudinally movable sleeve encircling the driving shaft and encompassing the nut and yielding driving connection, such sleeve co-

operating at its forward end with the pinion and adapted to move it longitudinally and a second sleeve yieldably connected to the first sleeve for normal movement longitudinally in unison therewith and having a spiral slot and pin connection with the rearward end of the first sleeve.

10. An engine starter drive including a rotatable driving shaft, a sleeve encircling such shaft, a screw threaded hollow shaft mounted on the driving shaft and extending partially into such sleeve, a pinion loosely mounted on the screw shaft and in advance of the sleeve, a nut threaded on the screw shaft and normally positioned at the front end of the sleeve, said nut being adapted to cooperate with and actuate the pinion, a drive head secured to the driving shaft, a drive spring between such head and the screw shaft, said sleeve encompassing the head and spring, and a second sleeve operatively connected with the rear end of the first sleeve by a spiral slot and pin connection.

11. An engine starter drive including a rotatable shaft, a driving member loosely mounted thereon for longitudinal movement into engagement with a member of the engine to be started, means for yieldingly holding such driving member in a normal position of disengagement, manually operated means for shifting such driving member into engagement with the engine member, and a control member mounted for longitudinal movement to clamp the driving member into driving relation with the shaft when the latter is started.

12. An engine starter drive including a rotatable shaft, a driving member loosely mounted thereon for longitudinal movement into engagement with a member of the engine to be started, means for yieldingly holding such driving member in a normal position of disengagement, manually operated means for shifting such driving member into engagement with the engine member, and automatically operating means for establishing driving relation between the driving member and the shaft when the latter is rotated.

13. An engine starter drive including a central motor driven shaft, a hollow screw shaft mounted thereon, a pinion loosely mounted on the screw shaft and adapted to be shifted longitudinally into engagement with a member of the engine to be started but normally disengaged therefrom, manually operated means for so shifting the pinion longitudinally, a yieldable driving connection between the shaft and sleeve, a nut threaded on the sleeve and movable longitudinally therewith to establish driving relation between the sleeve and pinion when such sleeve is rotated, and means for withdrawing the pinion from engagement when the engine operates under its own power.

14. An engine starter drive including, in

combination with a starting motor, a driving member adapted to be shifted into operative engagement with a member of the engine to be started and to be driven by the motor, and combined means for shifting the driving member longitudinally and for rotating the same, including a shifter, a member movably connected to said shifter and adapted for longitudinal movement therewith into engagement with said driving member, and means normally maintaining the member connected to the shifter in a predetermined position relative to said shifter, said member connected to the shifter being adapted for angular movement relative to said shifter when in engagement with said driving member.

15. An engine starter drive including, in combination with the starting motor, a driving member adapted to be shifted into operative engagement with a member of the engine to be started and to be driven by the motor, and means outside the line of transmission of torque for shifting the driving member, said means including a shifter, a toothed member operatively connected to said shifter and adapted for movement relative thereto, said last named member being moved by said shifter into abutting engagement with the driving member, and yielding means for normally maintaining said toothed member in a predetermined position relative to said shifter.

16. An engine starter drive including, in combination with a starting motor having an armature shaft, a driving member mounted for rotary and longitudinal movement on said shaft and adapted to be shifted into operative engagement with a member of the engine to be started and to be driven by the motor, and yielding means for normally maintaining said driving member out of engagement with said engine member, and common means for longitudinally shifting said driving member into engagement with the engine member and for rotating said driving member in the event of abutting of the same with the engine member, said common means including a manually operable lever, a member operatively connected to said lever and adapted for pinion rotating movement relative thereto, said last named member being movable into abutting engagement with the non-engaging end of the driving member, and yielding means for normally maintaining said movably mounted member in a predetermined position relative to said lever, said driving member being movable out of engagement with the engine member independently of said shifting means.

17. An engine starter drive including, in combination with a starting motor, a pinion operatively connected with the motor and adapted to be shifted into engagement with a member of the engine to be started, and an

operating device for shifting said pinion longitudinally into mesh with the engine member, said device including a lever and an angularly movable, toothed member outside of the line of transmission of torque and operatively connected to said lever, adapted to be moved into abutting engagement with the pinion.

18. An engine starter drive including, in combination with a starting motor, a spirally threaded motor-driven shaft, a driving member adapted to be shifted to engage a member of the engine to be started but normally disengaged therefrom, said driving member being mounted on the threaded portion of said shaft, and manual means for so shifting the driving member, including a lever and angularly movable means interposed between the driving member and lever and movably connected to the lever, said angularly movable member being adapted for engagement with said driving member and the latter being movable out of engagement with the engine member independently of said shifting means.

19. An engine starter drive including, in combination with a starting motor, a pinion adapted to be shifted into mesh with a member of the engine to be started but normally disengaged therefrom, said pinion being provided with irregularities on the non-engaging end thereof, and common means for shifting and rotating said pinion into operating engagement with said engine member, including a pivotally mounted lever and a member operatively and movably connected to said lever and adapted to be moved into engagement with the irregularities on said pinion.

20. An engine starter drive including a rotatable shaft, a driving member mounted for longitudinal movement thereon into engagement with a member of the engine to be started and having on its non-engaging end a series of irregularities, means for rotating said driving member with said shaft when engaged, and manually operable means adapted to cooperate with said non-engaging end of the driving member, including a shifter and means interposed between the shifter and driving member for shifting said driving member axially into mesh with said engine member and in such movement rotating said driving member in the event the latter abuts said pinion member.

21. An engine starter drive including a rotatable shaft, a driving member mounted for longitudinal movement thereon into engagement with a member of the engine to be started and having on its non-engaging end a series of irregularities, means for rotating said driving member with said shaft when engaged, and manually operable means adapted to shift such driving member into engagement with the engine member and by

- the same direction of movement to rotate the driving member in the event of its abutting the engine member, said manually operable means including a shifter and a member movably connected with said shifter and adapted to engage said irregularities of said driving member, said last named member and driving member being relatively rotatable when such driving member is driving the engine member.
22. An engine starter drive including a rotatable shaft, a driving member mounted for longitudinal movement thereon into engagement with a member of the engine to be started and having on its non-engaging end a ring of teeth, means for rotating said driving member with said shaft when engaged, and manually operable means adapted to shift such driving member into engagement with the engine member and by the same direction of movement to rotate the driving member in the event of its abutting the engine member, said manually operable means including a shifter and a member movably connected with said shifter and adapted to engage said teeth of said driving member, said last named member and driving member being relatively rotatable when such driving member is driving the engine member.
23. An engine starter drive including a rotatable shaft, a driving member mounted for longitudinal movement thereon into engagement with a member of the engine to be started, said driving member being in the form of a pinion having a ring of teeth on its non-engaging end, means for rotating said pinion with said shaft when engaged, and manually operable means for shifting said driving member longitudinally and for rotating the same into mesh with the engine member, including a pivotally mounted shifter and a toothed member operatively connected to said shifter and adapted to engage said teeth on the non-engaging end of said pinion.
24. An engine starter drive including a rotatable shaft, a driving member mounted for longitudinal movement thereon into engagement with a member of the engine to be started, said driving member being in the form of a pinion having a ring of teeth on its non-engaging end, means for rotating said pinion with said shaft when engaged, and manually operable means including a member longitudinally movable to contact and cooperate with said teeth to shift the pinion into engagement with the engine member, and means to impart an angular movement to said longitudinally movable member to rotate the pinion slightly in the event the latter abuts the engine member, said longitudinally movable member being normally out of engagement with the pinion.
25. An engine starter drive comprising, in combination, a rotatable drive-connecting member movable axially into driving relation with a rotatable part of the engine to be started; automatic means for disconnecting the drive-connecting-member from the engine part when the engine starts; and a manually operable device for moving the drive-connecting-member into driving engagement with the engine part, said device including two constantly connected members, one of which is rotatable coaxially of the drive-connecting-member, means for connecting the drive-connecting-member with the rotatable, manually operable member, and means for connecting the manually operable members for endwise movement together, or so that endwise movement of one member relative to the other will effect rotation of the rotatable, manually operable member.
26. An engine starter drive comprising, in combination, a rotatable drive-connecting-member movable axially into driving relation with a rotatable part of the engine to be started; automatic means for disconnecting the drive-connecting member from the engine part when the engine starts; and a manually operable device for moving the drive-connecting-member into driving engagement with the engine part, said device including a member rotatable coaxially of the drive-connecting-member and movable axially into engagement with the drive-connecting member, means for rotatively connecting said members, a manually operable part movable along the rotatable, manually operable member and constantly connected therewith, and means for connecting the manually operable part and member so that they may move together and so that, in case axial movement of the rotatable manually operable member is arrested, further movement of the manually operable part will effect rotation of the manually operable member.
27. Engine starting apparatus comprising, in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; and manually operable means for shifting the pinion endwise into mesh with the engine gear and for rotating the pinion in case the pinion teeth collide with the engine gear teeth, said means including two members movable along the shaft, one of said members being rotatable, and one of said members having a part located oblique to the direction of bodily motion of said members and engaged by the other member whereby the rotatable, manually operable member may be rotated by the other member when moved along the shaft, and means for connecting the rotatable member with the pinion.
28. Engine starting apparatus comprising,

in combination, a motor; a shaft operated by the motor; means for connecting the shaft with the gear of an engine to be started and including a pinion mounted on the shaft for longitudinal movement thereof and rotary movement therewith and provisions whereby the pinion will be automatically demeshed from the engine gear when the engine starts; a device for shifting the pinion endwise into mesh with the engine gear and for rotating the pinion in case the pinion teeth collide with the engine gear teeth, said device including two members movable longitudinally of the shaft, said members having an oblique slot and pin connection with each other for movement together longitudinally of the shaft and for angular movement one relative to the other when longitudinal movement of one of the members is obstructed, said member being adapted to shift the pinion longitudinally and to rotate the pinion, and manually operable means for actuating said device.

29. Engine starting apparatus comprising, in combination, a motor; a motor switch; a shaft having spiral splines driven by the motor; a pinion normally connected with the splined portion of the shaft for longitudinal movement into mesh with an engine gear and for rotary movement with the shaft; a manually operable member for closing the motor switch; and means for transmitting motion from the manually operable member to the pinion to mesh the pinion with gear, said means preventing closing the motor switch until after the pinion partly meshes with the gear, and said means including a pin element and an element having a slot oblique to the shaft and engaged by the pin, said elements being movable together along the shaft, and one of them engageable with the pinion and having provisions adapted to impart rotation to the pinion in case the pinion teeth collide with the engine gear teeth.
